UNITED STATES PATENT OFFICE.

SAMUEL C. L. BRINE, OF LOS ANGELES, CALIFORNIA.

HAT-PIN PROTECTOR.

1,069,845.

Specification of Letters Patent.

Patented Aug. 12, 1913.

Application filed January 30, 1911. Serial No. 605,411.

To all whom it may concern:

Be it known that I, SAMUEL C. L. BRINE, a subject of the King of Great Britain, and residing at Los Angeles, in the county of 5 Los Angeles and State of California, have invented new and useful Improvements in Hat-Pin Protectors, of which the following is a specification.

This invention relates to improvements 10 in protectors for hat pins or other pointed instruments and is particularly designed for use in connection with an ordinary hat pin employed by ladies in holding their hats in place.

15 The present invention is an improvement upon the device previously described and claimed by me in my application for patent S. N. 592,820, filed November 17, 1910, for hat pin protectors.

20 It is an object of the invention to provide a guard or protector which can be readily and quickly put in place upon the point of a pin or other instrument and while guarding the point and protecting it from accidentally engaging objects or people other 25 than the wearer of the device, it is yet ornamental and of a simple and neat construction.

It is a further object of the invention to 30 provide ornamental guarding means for the point of the pin which can be elongated or shortened as found desirable.

In the accompanying drawing forming a part of this specification, Figure 1 is a 35 longitudinal central sectional view through the improved hat pin protector, a pin engaging the same being shown in side elevation. Fig. 2 is a similar longitudinal sectional view showing the protector without 40 the exterior ornamental portion illustrated in Fig. 1. Fig. 3 is a transverse cross sectional view taken upon the line 3—3 of Fig. 1. Fig. 4 is a longitudinal sectional view of the protector made slightly different 45 from that illustrated in Fig. 2 and provided with a different form of spring gripping means. Fig. 5 is a transverse sectional view taken upon the line 5—5 of Fig. 4. Fig. 6 is a detail perspective view of the 50 spring employed in the protector illustrated in Figs. 4 and 5.

The parts of the device will now be more particularly described, reference being had to the drawing, in which 10 indicates the 55 body portion of the protector, 11 a telescoping movable part mounted therein, and 12

a spring gripping means carried by the said protector.

The protector 10 is formed with an elongated body portion which may be cylindrical, rectangular, or other desired shape in cross section, and which near one end is provided with enlarged projecting portions 60 13 which form lateral extending recesses in which the spring gripping devices 12 are 65 located.

On the outer wall of the enlarged portion 13 an entrance opening for the hat pin is provided at 14 and a flaring flange 15 is secured around said opening so as to receive 70 the point of the pin and direct it toward the opening.

The enlarged portion 13 is preferably made up of a plurality of laterally projecting housings, usually arranged opposite each 75 other in pairs for receiving the spring grippers 12 as clearly indicated in Fig. 3. The grippers 12 are preferably formed of spring wire of similar material bent back and forth upon itself, to provide gripping folds, into 80 which the point of the pin to be held may be thrust. There may be any number of folds employed, as indicated in Fig. 3, but by bending the spring material about three times, spring grippers of suitable size are 85 usually provided. The folds of said springs normally lie side by side in approximately straight condition, but will yield and may be forced aside as shown in Fig. 3 when a pin is forced between them. The pin may engage 90 any of the folds of the springs and be properly held in place. I preferably employ two of these bent and folded springs 12 as indicated in the drawing, one being arranged transversely with respect to the 95 other, and in this manner the pin is gripped upon at least four different sides. The gripping material being of metal as for instance spring wire, engages the pin with a sufficiently positive grip to properly hold it 100 from slipping out of the protector, and yet it is always possible to readily and easily withdraw or insert the pin, since the metal of the pin will slide more or less readily upon the metal of the grippers. 105

While the body portion 10 of the protector may be made of any desired length it is preferably made comparatively short and an inner telescoping part 11 is provided having an enlarged bearing end or flange 16, sliding 110 within the body portion 10 and preventing the disengagement of the telescoping por-

tion 11 therefrom. The end of the body portion 10 is turned inwardly to form a retaining flange at 17 for limiting the movement of the telescoping portion 11. The part 11 5 may be adjusted by moving it in and out to the desired depth to which it is intended to insert the hat pin.

The outer contour of the protector may be made in plain lines or may be given more 10 fanciful shapes and as shown in Fig. 1 may carry outside ornamental portions as for instance the part 18 which is secured outside the body portion 10 and an ornamental cap 19 which is carried by the end of the telescoping part 11. The inner edge of the cap 19 preferably telescopes over the end of the ornamental part 18 so that the adjustment 15 of the protector is not interfered with.

It will be apparent that the outer shape or 20 fanciful designs employed may be varied in accordance with the taste of the manufacturer or the wearer within the spirit of the invention. The spring gripping means may also be varied within the spirit of the invention, thus as shown in Figs. 4, 5, and 6 a 25 bent clip shaped spring of approximately flat material as shown at 20 may be used. In this instance the material is bent double with a looped portion formed at 21 which is provided with an aperture 22 therein through 30 which the point of the pin may project or through which the pin may extend when pushed to a considerable distance into the protector. The flat portions of the spring 35 normally bear upon each other and are provided with elongated facing grooves as at 23, for directing and maintaining the hat pin in the longitudinal central portion of the gripping spring. The ends of the spring 40 material are spread apart and turned outwardly as at 24 to insure the proper entrance of the pin point between the side portions of the spring. In springs of this character the spread parts 24 of the spring are located in 45 an annular casing or housing 25 formed upon the end of the hat pin protector which is provided upon its outer face with a conical surface 26 leading to a central pin receiving aperture 27. The loop or bent portion 50 21 of the spring preferably extends into the telescoping section of the protector as clearly shown in Fig. 4.

It will be understood that the protector is applied to the ordinary hat pin after the 55 same has been inserted and pushed through the hat of the wearer, by merely pushing the

protector upon the pointed end of the said pin. The pin will force its way between the yielding parts of the spring grippers and will be clamped thereby, so as to prevent the 60 protector from slipping from place. The length of the protector may be adjusted in accordance with the length of the projecting end of the pin, by means of its telescoping sections. 65

The device is useful in connection with all slender pointed instruments where it is desired to cover the point thereof and prevent its exposure to view or its coming in contact with articles or people. 70

What I claim is—

1. A pin protector, comprising a housing formed of outer and inner telescoping sections in frictional engagement one with the other, one section being free to slide within the other, pin gripping springs mounted within the outer section adapted to prevent the accidental displacement of the protector from a pin, and means formed on both sections adapted to limit the outward movement of the inner section and to prevent a detachment of said sections. 75

2. A pin protector, comprising a housing formed of outer and inner telescoping sections in frictional engagement one with the other, one section being free to slide within the other, transversely arranged folded springs loosely mounted within the outer section, means on said outer section holding one folded spring so as to extend transversely of the other, whereby a plurality of yielding folds are presented for receiving the point of the pin and holding it in position in said section, and means formed on both sections adapted to limit the outward movement of the inner section and to prevent a detachment of said sections. 80

3. A pin protector comprising inner telescoping pin receiving casings and outer telescoping ornamental coverings carried by 100 said inner casings, whereby the length of the protector may be varied as desired without losing the ornamental appearance of the exterior of the protector, and spring gripping means mounted within the protector. 105

In witness that I claim the foregoing I have hereunto subscribed my name this 20th day of January, 1911.

SAMUEL C. L. BRINE.
